UNITED STATES PATENT OFFICE

2,575,054

INFANT'S DIAPER COVER

William F. Gowdy, Milford, Mass., assignor to
 Archer Rubber Company, Milford, Mass., a cor-
 poration of Massachusetts

Application April 5, 1950, Serial No. 154,139

2 Claims. (Cl. 128—287)

1

This invention relates to garments and more especially a baby pant or cover to be worn over the diaper, having a moisture-resistant inner side and an attractive outer side.

The principal objects of the invention are to provide a garment which may be laid flat beneath the infant for folding about the limbs, thus facilitating application; which, when applied, will cover the diapered portion of the body snugly and neatly; and which will have a minimum of fastening elements for securing the parts in place without subsequent gaping when the child moves about.

As illustrated the garment is one-piece in extent and consists of two layers, the inner layer being of a water repellent material such as thin sheet plastic, rubber or rubberized cloth and an outer layer of woven or knitted textile material which affords an attractive finished surface, the two layers being joined by stitching throughout their peripheral edges but otherwise unjoined. This piece is roughly of T shape, comprising a horizontally elongate body portion of generally rectangular shape having a substantially straight upper edge and having convex lateral edges; a crotch portion extending downwardly from the body portion and symmetrically arranged with respect to the lateral edges of the body portion, said crotch portion having deeply concave, lateral edges which define the leg openings, when the garment is in use, and a front or abdominal portion extending downwardly from the crotch portion and having a deeply convex lower edge approximately a half-circle in arcuate extent and which intersects the concave edges of the crotch portion at substantially right angles. When in use, the right and left parts of the body portion extend forwardly to wrap about the thighs with the ends of the upper edge of the body portion meeting in front at waist level and with the upper lateral portions of the elongate body overlapping the front member of the garment so as to cover substantial areas of the latter. Only three fasteners are required for holding the garment in the position of use. One of these fasteners unites the upper corners of the body portion to the center of the front or abdominal portion thereby defining the waist opening while the other two fasteners unite the lower corners of the body portion to the lower corners respectively of the crotch portion thereby defining the leg openings.

The lateral edges of the body portion are convex and when the upper corners of the body portion are lapped over the front portion in use, the areas of overlap are of lenticular shape of maxi-

2

mum width substantially midway between the waist and leg fasteners, said maximum width being the sum of the altitudes of the arcuate edges of the overlapping portions thereby affording ample opportunity for lateral displacement of the parts without gape.

The invention will now be described in greater detail with reference to the accompanying drawings wherein:

- 10 Fig. 1 is a front elevation of the garment as it would be worn;
- 15 Fig. 2 is a plan view of the garment opened out flat;
- 20 Fig. 3 is a section on the line 3—3 of Fig. 1 showing the fastening element for the waistband portion thereof; and
- 25 Fig. 4 is a fragmentary portion of the upper corner of one of the foreparts showing a grommet fastened thereto.
- 30 Referring to the figures and in particular to Fig. 2, there is shown the garment laid out flat prior to folding about the body of the infant for covering the diaper. As illustrated the garment is one-piece in extent and consists of two layers, the inner layer being a water-repellent material such as thin sheet plastic, rubber or rubberized cloth and an outer layer of woven or knit textile material which affords an attractive finished surface, the two layers being joined by stitching throughout their peripheral edges but otherwise unjoined. As illustrated the body portion 14 of the garment is transversely elongate and substantially rectangular. This body portion has outwardly convex, lateral edges 20 and an upper edge 16 which is substantially rectilinear. The central part of the body portion constitutes the back of the garment when it is in use, while more or less triangular upper corner areas 18 of the body portion wrap about the thighs when the garment is in use and form what are hereafter referred to as the side and forepart portions. The lateral edges 20 are bowed outwardly or convex. From the lower part of the body portion the crotch portion 26 extends downwardly, being symmetrically disposed as respects the lateral edges 20 of the body portion and having deeply concave lateral edges 28, approximating half-circles in shape and extent. From the lower part of the crotch member 26 the front or abdominal portion 22 of the garment extends, this front portion having a lower edge 24 which is deeply convex and which intersects the concave edges 28 of the crotch portion at substantially right angles, these concave edges also intersecting the lateral edges 20 of the body
- 35
- 40
- 45
- 50
- 55

portion at substantially right angles. Along the edge 16 there is stitched an elasticized element 30 and along the edges 28 there are stitched elasticized elements 32. As thus constructed the garment may be folded for placing about the body of the wearer by first placing the infant buttocks-down on the central part of the flat body portion 14 of the garment, substantially midway between the edges 20, with the front part 22 between the legs, and then bringing the front part 22 upwardly between the legs about the crotch and over the abdomen until the midpoint of the edge 24 of the front or abdominal portion is substantially level with the upper edge 16 of the body portion. The side and foreparts 18 are then wrapped forwardly around the thighs of the wearer and lapped over the face of the front part 22 until the edges 20 meet at waist level in a slightly overlapping relation (Fig. 1). As thus folded the edges 20 extend downwardly in drape fashion from the waist level and at their lower ends, meet the lower extremities of the side edges 24.

In accordance with the present invention only three fasteners are required for holding the garment in the position of use. As here illustrated the fastening means for securing the parts in the position of use are snap fasteners, one of which is located at the front of the waistband and one of which is located at each leg opening. The fastener which is at the front of the waistband may, for example, be of the type specifically illustrated in Fig. 3. This fastener comprises a headed stud 34 anchored by means of base flanges 36 to the front member 22 of the garment at a point close to the edge of the latter and midway between the right and left ends of said edge. At one end of the upper edge 16 of the body portion of the garment, for example at its right-hand end, as shown in Fig. 2, there is provided a grommet 42 having a central opening of a size to permit free passage of the stud 34. To the opposite or left-hand end of the body portion, there is attached a socket member 38 complementary to the stud 34 to form a conventional snap fastener, this socket member comprising a cap and interlocking ring 40. The stud 34 is long enough so that it may be passed through the grommet 42 and then engaged with the socket member 38, thus simultaneously attaching both ends of the waistband of the body portion to the front member 32. If desired, a pull tape 41 may be anchored to that corner of the garment at which the socket 38 is located.

The snap fasteners for the leg openings are conventional and consist of parts 44 and 46 situated at the ends of the convex edges 28 at opposite sides of the garment.

The front part 22, as heretofore pointed out, is generally sector-shaped and is made of sufficient area so that its lateral side edges 24 extend beneath the forward edges 20 of the side and forepart portions 18. As illustrated, the edges 24 extend laterally almost to the hip bone and the edges 20 drape from the waist to the leg openings thereby affording substantially lenticular-shaped opposed areas at each side of the central portion of the garment thus eliminating gaping by relative movement of the parts.

The overlap midway between the waist and leg openings is approximately twice the altitude of the chordal area (defined by an edge 20 and a chord x-x drawn through the fasteners at the leg and waist end) and tapers from this mid-maximum overlap to a minimum at the leg and

waist. Thus the greatest overlap is midway between the fasteners and hence at the place where gap would be most likely to occur.

The garment produced as described heretofore in contrast to the great majority of garments of this kind made heretofore has the forepart portions overlapping the front part rather than underlying it, the advantages of which are that there are no upwardly facing pocket-like openings into which objects such as pins or food may drop and thus gain entrance to the inside of the garment to the danger and discomfort of the infant. Furthermore, while there have been garments made wherein the side parts are fastened to the outside of the front, the overlap is small and to prevent gap a large number of fasteners had to be used which is undesirable.

It should be understood that the present disclosure is for the purpose of illustration only and that this invention includes all modifications and equivalents which fall within the scope of the appended claims.

I claim:

1. A baby garment having a body portion comprising a back and side and forepart portions, the body portion having convexly curved lateral edges and a substantially rectilinear upper edge, a front portion having a deeply convex lower edge, of approximately half-circular contour, and a crotch portion integrally joining the front and body portions, said crotch portion having lateral, deeply concave edges intersecting the respective lateral edges of the body portion at substantially right angles, and intersecting the opposite ends respectively of the convex edge of the front portion at substantially right angles, the garment being characterized in that, when in use, the forepart portions of the body portion overlie the front portion of the garment to form a two-ply area of lenticular shape and of a maximum width, midway between the waistband and leg opening which is the sum of the altitudes of the arcuate edges of the overlapped portions, and with the upper corners of the body portion meeting the mid-portion of the convex edge of the front portion of the garment substantially at the waist level thereby defining a waist opening and with the lower corners of the body portion meeting the front portion at the respective ends of its convex edge, the parts of the garment being held in the position of use by three fasteners, only, located respectively, one at the front of the waistband, and the others at the fronts of the leg openings, whereby the lateral edges of the body portion are free to move, relatively to the front portion from the waistband fastener to the respective leg opening fastener.

2. A one-piece garment having a body portion comprising a back and side and forepart portions, the body portion having a substantially straight upper edge and convex lateral edges, the garment also comprising a front or abdominal portion having a convex lower edge, of approximately half-circular curvature, and a crotch portion integrally joining the body portion and front portion, said crotch portion having deeply concave edges, approximately half-circular in contour and which at their upper ends intersect the lateral edges of the body portion, and at their lower ends intersect the convex edge of the front portion, characterized in that a contractile element is associated with the upper edge of the body portion to form an elastic waistband and that contractile elements are associated with the concavely curved edges of the crotch portion to

form elastic leg openings, the lateral parts of the body portion extending forwardly when the garment is in use with marginal areas arranged to overlie substantial areas of the front portion of the garment, the areas of overlap being lenticular in shape and each of a maximum width, approximately midway between the waistline and leg opening, substantially equaling the sum of the altitudes of the arcuate edges of the overlapped portions, the body portion having fastener elements at opposite ends of its upper edge and the front portion having a waistband fastener element substantially midway between the ends of its convex edge, the latter fastener element being engageable simultaneously with the aforesaid two fastener elements at opposite ends of the body portion thereby to join the front portion to the body portion at the waistline, and complementary fastener elements at opposite ends of the concavely curved edges of the crotch portion oper-

ative to unite the lower corners of the body portion to the upper corners of the front portion thereby to define the leg openings, the marginal areas of the body portion which overlap the front portion being free of any connection to the front portion between the waistband fastening and the respective leg opening fasteners.
